UNITED STATES PATENT OFFICE.

LUTHER D. LOVEKIN, OF PHILADELPHIA, PENNSYLVANIA.

PUMP-GOVERNOR.

1,294,497.

Specification of Letters Patent. Patented Feb. 18, 1919.

Application filed February 23, 1916. Serial No. 79,856.

To all whom it may concern:

Be it known that I, LUTHER D. LOVEKIN, a citizen of the United States of America, and a resident of Philadelphia, county of 5 Philadelphia, and State of Pennsylvania, have invented a certain new and useful Improvement in Pump-Governors, of which the following is a true and exact description, reference being had to the accompanying 10 drawings, which form a part thereof.

My present invention consists in an improved pump governor for automatically regulating the supply of steam to the driving element of a steam pump in response to 15 the pressure at which the liquid pumped is discharged from the pump. The object of my invention is to provide a governor for the purpose specified, characterized by its simplicity, and by the absence of frictional 20 resistance, and particularly of stuffing box resistance to its operation whereby a desirable sensitiveness and accuracy, as well as reliability of operation, are assured.

The various features of novelty which 25 characterize my invention are pointed out with particularity in the claims annexed to and forming a part of this specification. For a better understanding of the invention, however, and the advantages possessed by 30 it, reference should be had to the accompanying drawings and descriptive matter in which I have illustrated and described a preferred embodiment of my invention.

Of the drawings:

35 Fig. 1 is a sectional elevation of a preferred embodiment of my invention;

Fig. 2 is a somewhat diagrammatic representation of a pumping unit provided with my improved governor; and

40 Fig. 3 is a view taken similarly to Fig. 1 of a portion of a governor of slightly modified construction.

The pump governor construction illustrated in Fig. 1 is collectively designated by 45 the reference symbol A. This governor, in the form shown, comprises a steam valve casing body B formed with an inlet chamber B' and an outlet chamber B² connected together by aligned ports B³ as is usual in balanced valves. The balanced valve member C controlling the ports B³ is provided with valve stem extensions or piston portions C' and C² at opposite sides of the valve disks. The stem extensions C' and C² work in 50 guide chambers B⁴ and b' respectively. As shown, the chamber B⁴ is formed in an inte-

gral extension of the valve body B, while the chamber b' is formed in a bonnet member b secured to the valve body B and closing an opening in the side of the inlet chamber B' in axial alinement to the ports B³. The guide chamber b' opens at its outer end into a larger chamber b² formed in the bonnet member b. Steam or water of condensation leaking along the valve stem C² through 60 the chamber b' passes into the chamber b², and steam or water of condensation leaking along the valve stem C' into the outer end of the chamber B⁴ also passes into the chamber b² through the leakage passage C⁴ formed 65 in the valve stem. The steam or water of condensation passing into the chamber b² escapes through the pipe O. The valve stem C² projects through the outer end of the chamber b². To prevent leakage along 70 the valve stem C², under certain conditions, as hereinafter explained, a stuffing box b³ is provided at the extreme outer end of the member b.

The steam valve B is connected to the 80 wall of the pressure chamber E by a cutaway barrel or cage member D which surrounds the outer end of the valve stem C² and an alined extension of the latter formed by a member G which is secured to the valve 85 stem C² by the coupling H. The member G bears at its lower end against the floating piston F working in the pressure chamber E. The delivery pressure of the pump is transmitted to the lower end of the chamber 90 E through the pipe K. The lower end of the member G fits in an open ended guide chamber or sleeve J' formed in a member J which closes the otherwise open upper end 95 of the chamber E. The member J is formed with a chamber J² surrounding the sleeve J' and in direct communication with, and really forming an enlarged extension of the chamber E. The chamber J² receives liquid which leaks past the piston F in the upper end of the chamber E. The liquid passing into the chamber J² escapes from the latter through the pipe P. To prevent leakage of air into the chamber J² along the stem extension G under certain conditions herein- 100 after explained, a stuffing box J³ is formed at the upper end of the member J. The upward thrust of the stem extension G of the floating piston F is opposed by the leading spring I surrounding the rod G and bearing 105 at its upper end against the transverse portion D' of the member D, and at its lower

end against the adjustable nut G' threaded on to the member G .

To restrict leakage while at the same time avoiding appreciable frictional resistance to the movement of the valve member, the piston portions C' and C^2 working in the guide chambers B^4 and b' , are advantageously formed with shallow steam and water grooves C^3 . Similarly the portion of the stem member G working in the sleeve J' is provided with grooves G^2 , and the floating piston F with grooves F' . While I ordinarily prefer to employ the governor with the valve member C and piston F vertically movable as shown, it will be understood that this is not strictly essential.

In Fig. 2 I have illustrated the use of my governor to control the operation of an ordinary reciprocating steam pump for pumping water into a tank, fuel oil to burners, or generally where it is desired to maintain a constant delivery pressure of the liquid pumped. In the pump shown in Fig. 2, L represents the pumping cylinder and LA the steam motor cylinder. The delivery pipe K' from the cylinder L is connected to the lower end of the chamber E by the branch pipe K . In this form of my invention the pipe P for conveying leakage away from the chamber J^2 is connected to the suction inlet pipe K^2 of the pumping cylinder L . The steam supply pipe M is connected to the inlet chamber B' of the steam valve B , and the outlet chamber B^2 of the steam valve is connected to the valve of the steam cylinder LA of the motor by the pipe section M' . In this form of my invention the escape pipe O for the steam and water passing into the chamber b^2 is connected to the exhaust pipe M^2 from the steam cylinder LA .

With the construction described it will be apparent that the frictional resistance to the movement of the valve member C in instant and direct response to variations in the pump delivery pressure acting against the lower end of the piston F , is reduced to a practical minimum. The stem G while constantly bearing against the floating piston F is preferably not mechanically connected thereto so that there is no tendency of the parts to cramp or bind. The parts are so constructed as to facilitate an accurate alinement and thus avoid all cramping and binding. The elongated contact surfaces between the walls of the chambers B^4 , b' and E , and the interior of sleeve J' and the parts working therein, especially when the latter are formed with the steam and water grooves as shown, make it possible to keep the leakage down to a relatively small amount, without requiring a fit close enough to introduce appreciable friction.

The stuffing box b^3 is provided to prevent leakage of air into the chamber b^2 and

its discharge into the exhaust pipe M^2 , which would be objectionable when the latter is connected to a condenser as is frequently the case, especially for marine work. Similarly, the stuffing box J^3 is provided to prevent the leakage of air into the chamber J^2 and its discharge into the pump line. The stuffing boxes b^3 and J^3 may be made effective to prevent an objectionable leakage of air under the conditions of use referred to, while offering a frictional resistance to the operation of the device which is but a small fraction of that which would exist in practice, if the stuffing boxes were employed to prevent the escape of steam from the steam valve B , and the escape of the liquid pumped from the pressure chamber E .

When either of the pipes O and P discharges against atmospheric pressure as each may well do in many cases, the corresponding stuffing box may be omitted, as in the construction shown in Fig. 3. In the last mentioned figure, the member ba , replacing the member b of Fig. 1, differs from the latter in the omission of the stuffing box b^3 and the member JA , replacing the member J of Fig. 1, differs from the latter in the omission of the stuffing box J^3 .

While in accordance with the provisions of the statutes I have illustrated and described the best form of my invention now known to me, it will be apparent to those skilled in the art that changes can be made in the form of my invention without departing from its spirit, and that some features of my invention can be used without a corresponding use of other features of the invention.

Having now described my invention, what I claim as new and desire to secure by Letters Patents, is:

1. A pump governor comprising in combination a valve casing divided into inlet and outlet compartments and formed with aligned valve spindle guide chambers, one of which has an open outer end for the passage of the spindle, and both of which have vented chambers for collecting and discharging fluid leaking along the guided spindles of the valve whereby it is made possible to avoid the use of tight packing, a balanced valve member in said casing provided with spindle portions working as pistons loosely held in said spindle guide chambers, and an external automatic valve controlling means operating on the valve spindle extending through its guide.

2. A pump governor comprising in combination a motive fluid valve casing divided into inlet and outlet compartments and formed with aligned guide chambers leading away from the interior of said valve casing and formed one with a closed, and the other with an open outer end, a valve

member in said valve chamber provided with piston portions working in said guide chambers and formed with a leakage passage leading from the outer end of the guide

- 5 chamber having the closed end through the piston portion working in the other guide chamber, and an external automatic valve controlling means engaging and operating said valve member through the open end of
 10 said open ended guide chamber, said casing having provisions for collecting and freely discharging leakage fluid passing to the open end of said open ended guide chamber through said leakage passage or by leaking
 15 past the piston portion working in said chamber.

3. A pump governor comprising in combination, a housing formed with a motive fluid valve chamber divided into inlet and outlet compartments, a pressure chamber open at one end and provided with a pressure fluid inlet to its opposite end, and guide chambers leading away from said valve chamber and one closed and the other open at its outer end, said guide chambers being in alinement with each other and with said pressure chamber, a valve member in said valve chamber provided with piston portions working in said guide chambers and formed with a leakage passage leading from the outer end of the guide chamber having the closed end, through the piston portion working in the other guide chamber, a piston working in said pressure chamber and an operating connection between said piston and valve member operating through the open ends of the open ended guide chamber and the pressure chamber, said housing being formed with provisions for collecting and freely discharging leakage fluid passing to the open end of said open ended guide chamber through said leakage passage or by leaking past the piston portion working in said chamber, and leaking past the piston working in said pressure chamber.

4. In combination a pressure fluid driven motor with supply and exhaust connections thereto, a pump driven by said motor and having suction and discharge connections thereto, and governing mechanism for said motor comprising a valve casing in said supply connection formed with alined guide chambers leading away from the interior of said valve casing one of said guide chambers being open at its outer end, a valve member in said valve chamber provided with piston portions working in said guide chambers, means placing the outer ends of said guide chambers in free communication with said exhaust connection, a pressure chamber connected at one end to said discharge connection and at the opposite end to said suction connection, a piston working in said pressure chamber and an operating

connection between said piston and valve member working through the open end of said open ended guide chamber.

5. In combination a fluid pressure motor with supply and exhaust connections thereto, a pump driven by said motor and having suction and discharge connections thereto, and a governing mechanism for said motor comprising a valve casing in said supply connection formed with alined guide chambers leading away from the interior of said valve casing, one of said guide chambers being open at its outer end, a valve member in said valve chamber provided with piston portions working in said guide chambers, a pressure chamber open at one end and connected at its other end to said discharge connection, a piston working in said pressure chamber, an operating connection between said piston and valve member working through the open ends of said pressure chamber and said open ended guide chamber, means placing the outer ends of said guide chambers in free communication with said exhaust connection and means connecting the open end of said pressure chamber to said suction connection.

6. A pump governor comprising in combination a motive fluid valve casing element divided into inlet and outlet compartments and formed with alined guide chambers leading away from the interior of said valve casing, a second casing element formed with a pressure chamber in alinement with said guide chambers and open at its end adjacent said guide chambers and having a fluid inlet to its opposite end, the outer end of the guide chamber adjacent said pressure chamber being open and the outer end of the other guide chamber being closed, a spacing element between said casing elements, a valve member in said valve chamber provided with piston portions working in said guide chambers and formed with a leakage passage leading from the outer end of the guide chamber having the closed end through the piston portion working in the other guide chamber, a piston working in said pressure chamber, an operating connection between said piston and valve member working through the open ends of the pressure chamber and adjacent guide chamber, said valve casing element being formed with a vented chamber for collecting and discharging fluid passing through said leakage passage or leaking past the piston portion working in said open ended chamber, and said second casing element being formed with a vented chamber receiving the leakage past the piston working in said pressure chamber.

7. A pump governor comprising in combination a motive fluid valve casing element divided into inlet and outlet compartments and formed with alined guide cham-

bers leading away from the interior of said valve casing, a second casing element formed with a pressure chamber in alignment with said guide chambers and open at its end 5 adjacent said guide chambers and having a fluid inlet to its opposite end the outer end of the guide chamber adjacent said pressure chamber being open and the outer end of the other guide chamber being closed, a 10 spacing element between said casing elements, a valve member in said valve chamber provided with piston portions working in said guide chambers and formed with a leakage passing leading from the outer end 15 of the guide chamber having the closed end through the piston portion working in the other guide chamber, a piston working in

said pressure chamber, and operating connection between said piston and valve member working through the open ends of the 20 pressure chamber and adjacent guide chamber, an adjustable loading device acting between said connection and said spacing element, said valve casing element being formed with a vented chamber for collecting 25 and discharging fluid passing through said leakage passage or leaking past the piston portion working in said open ended chamber, and said second casing element being formed with a vented chamber receiving the 30 leakage past the piston working in said pressure chamber.

LUTHER D. LOVEKIN.
